APPARATUS FOR SAMPLING FLUIDS IN GEOLOGICAL FORMATIONS

Maxime Felix Benoit Picard, Paris, France, assignor to Societe de Prospection Electrique Procedes Schlumberger, Paris, France, a corporation of France

Application October 15, 1953, Serial No. 386,279

Claims priority, application France October 25, 1952

8 Claims. (Cl. 166—100)

The present invention relates to apparatus for taking samples of fluids (liquids or gases) that are present in geological formations and in particular in the formations forming the side walls of wells drilled into the earth.

Explosively propelled hollow projectiles have been employed heretofore for sampling the contents of earth formations traversed by a well. In one such apparatus, the hollow projectile comprises a cover which is adapted to be sheared off when the forward part of the projectile reaches the formation to permit the introduction of fluid into a cavity therein. Valve means is provided which is adapted to be closed after the entrance of the fluid so as to prevent escape of the latter during the raising of the projectile to the surface of the earth.

Apparatus of the type described above has not been entirely satisfactory. For one thing, difficulty has been experienced when operating in a well containing drilling mud, for example, in preventing, to the maximum extent possible, the drilling mud from penetrating to the interior of the cavity in the projectile after the cover has been sheared off, and contaminating the fluid sample obtained from the formation constituting the adjacent wall of the well. Also, it has not always been possible to maintain good watertightness of the projectile after the taking of the sample and during the raising of the projectile up to the surface of the earth.

An object of the invention, accordingly, is to provide new and improved sample taking apparatus in which these difficulties are overcome in a satisfactory manner.

This and other objects of the invention are attained by providing a forward part for the projectile, which surrounds the cover that is to be sheared off, and which is made of a metal that is relatively malleable while at the same time having sufficient strength for the purpose. The hardness of this metal will preferably be chosen as a function of the hardness of the formations against which the sample taking device will be projected. In the case of consolidated sands or sandstones, a suitable metal in accordance with the invention might be aluminum, for example, exclusive of alloys such as Duralumin, etc. In the case of very hard limestone, on the other hand other types of metals may be employed.

Preferably, the forward part of the projectile should have a relatively large surface area and it should be shaped in the form of a frustum of a cone of large apex angle. By virtue of this construction, when the projectile is driven against the wall of the well, its forward part depresses a complementary portion of the wall and fits exactly against the resulting depression without rebounding so that it constitutes an effective joint forming a vent prolonging the duration of suction. Further, while it provides free communication between the interior of the projectile (after shearing of the cover) and the wall of the well, it is also of maximum effectiveness in preventing the bore hole liquid from reaching the orifice of the projectile. The presence of mud cake on the wall of the well in practice is a favorable factor, since this cake constitutes a natural watertight joint.

2

The invention further contemplates that the retaining valve disposed in the interior of the projectile will operate in response to differential pressures such that, as soon as fluid penetrates to the interior of the projectile 5 the valve closes and, as a result of the differential pressure exerted against its head, will maintain sufficient force to prevent reopening of the valve during the raising of the apparatus to the surface of the earth.

When only the fluid contained in sandy formations is 10 to be collected, to the exclusion of the sand in such formations, a filter constituted by a wire screen or other equivalent means may be placed before the entry orifice of the valve, in order to prevent the penetration of the sand into the receptacle intended to collect and retain the fluid.

Other objects and characteristics of the invention will appear during the course of the following description of a representative embodiment, taken in conjunction with the accompanying drawings in which:

20 Fig. 1 is a view, partly in transverse section, through sample taking apparatus constructed according to the invention and disposed in the interior of a well;

25 Fig. 2 is a view in longitudinal section of one of the sample taking projectiles in the apparatus shown in Fig. 1; and

Fig. 3 is a modification of the sample taking projectile shown in Fig. 2.

In Fig. 1, 1 designates a well containing a liquid such as drilling mud and traversing earth formations 30 2 which may be, for example, sands containing fluid (liquid or gas) of which a sample is to be taken. Within the well is disposed lateral sample taking apparatus 3 in which are formed hollowed out portions 4 constituting guns by means of which sample taking tools 6 may be projected against the wall of the well as the result of the explosion of powder charges 5. While in Fig. 1 only one sample taking tool is shown, actually the apparatus has formed therein a plurality of superposed hollowed out portions forming guns each containing a sample taking tool.

40 The sample taking tools 6 are connected to the body of the apparatus by cables 7 such that when the apparatus is raised to the surface of the earth the sample taking tools are carried along with it and also brought to the surface. This arrangement is well known per se in so far as concerns conventional lateral sample taking apparatus.

45 The purpose of the sample taking tool is to collect and retain samples of fluid contained in the well. To this end, it comprises (Fig. 2) a hollow cylindrical body in two parts 8 and 9 screwed to one another in order to facilitate manufacture and assembly. The body parts cooperate to form an interior chamber 10 in the body which is adapted to receive the fluid drawn off from the formation. The chamber 10 is normally closed at its forward end by a valve 11 comprising a cylindrical element 12 slidably mounted on a fixed piston 13. The piston 13 is secured to the body part 9 by means of a disc 14 pierced with holes to permit fluid to pass therethrough.

50 55 60 65 60 The piston 13 is secured to the body part 9 by means of a disc 14 pierced with holes to permit fluid to pass therethrough. Packing means such as a packing ring 15 may be disposed between the piston 13 and the interior wall of the cylinder 12 to insure watertightness. At the forward end of the cylinder 12 is formed a crown member 16 carrying in a groove packing means such as a packing ring 17 adapted to be applied against the forward wall portion 18 of the chamber 10.

A stop member 27 carried by the cylindrical body part 8 serves to limit the movement of the valve 11 rearwardly.

On the forward extremity 19 of the body 9 is fitted a head member 20 which is also cylindrical in shape, and a cavity 21 is formed between the head member 20 and the body forward extremity 19. Suitable packing means

such as a packing ring 22 assures watertightness between the body extremity 19 and the head member 20.

According to the invention, the head member 20 is made of a relatively soft metal such as pure aluminum, for example. In the front end of the head member 20 is formed an orifice 23 which is normally closed by a closure portion 24 formed integrally with the head member 20. The portion of the head member 20 surrounding the orifice 23 is relatively large and, in accordance with the invention, its forward face 25 is preferably shaped in the form of a frustum of a cone having a large apex angle.

In operation, the apparatus is lowered to the desired level in the well and the sample taking tools are projected in the known manner against the wall of the well by the explosion of the powder charges. However, while the conventional sample taking tools are constructed so as to penetrate deeply into the wall of the well, the apparatus in accordance with the invention, by virtue of the large surface 25, penetrates only relatively slightly into the wall of the well as can be seen in Fig. 1, the depth of penetration depending on the nature of the material. As a result of the violent shock which the tool undergoes against the wall of the well, the forward face 25 of the head member 20 is deformed so as to conform exactly to the irregularities in the formation constituting the wall of the well. At the same time, under the influence of the exterior pressure which is exerted against the closure portion 24, the latter is sheared off, whereupon the substance (sand imbibed with fluid, for example), constituting the wall of the well rushes into the interior of the chamber 21.

By virtue of the shaping of the forward face of the head member which, as stated previously, fits exactly and is retained against the wall of the well, the bore hole liquid cannot reach the orifice 23. Hence, substantially only the substance coming from the formation itself enters the chamber 21.

The substances which have thus penetrated the chamber 21 under the influence of the strong pressure which they exert push against the cylindrical element 12 and penetrate eventually the chamber 10 which they fill completely. The rearward movement of the cylindrical element 12, which is limited by the stop member 27, creates a vacuum in the space comprised between the piston 13 and the bottom of the interior of the cylindrical element 12. Hence, after the chamber 10 is filled, the cylindrical element 12 will close itself under the influence of the fluid pressure in the chamber 10.

As a result of the existence behind the piston 13 of a cavity which is at most at atmospheric pressure, the pressure of the substances contained in the cavity 10 is exerted over a much larger surface than that of the substances remaining outside of this cavity, so that the closure of the valve is effected under the action of a considerable force. There is no longer any risk, therefore, that the cylindrical element 12 will open during the raising of the apparatus to the surface of the earth.

After the apparatus has been brought to the surface, it is necessary only to unscrew the parts 8 and 9 in order to collect the substances contained in the cavity 10, or to again lower the cylindrical element 12 after having taken out the piston 13.

In case it is desired not to collect the sand contained in the formations, but only fluid, this may be done, according to the invention, by placing in front of the valve 11 and resting against the disc 14, for example, filter means constituted, for example, by a wire screen 30 or the like as shown in Fig. 3.

It will be understood that numerous modifications may be made in the specific embodiment disclosed without departing from the scope of the invention. Therefore, the latter is not to be limited to that embodiment but is to be considered as broadly as permitted by the appended claims.

I claim:

1. Apparatus for sampling the fluid content of geological formations and the like, comprising a hollow tubular projectile adapted to be projected into a formation, means forming a temporary closure for one end of said projectile, a transverse partition formed in said projectile, a rear closure member for said projectile cooperating with said partition to form a fluid storage chamber, means forming an orifice in said partition, a valve seat formed on said partition around said orifice inside said storage chamber, a valve head in said chamber adapted to cooperate with said valve seat for normally closing said orifice, means forming a blind bore in said valve head having its open end facing said orifice, and piston means mounted inside said projectile in fixed relation thereto and snugly received in said bore for fluid tight sliding movement of said valve head thereon to open and close said orifice, said valve head being actuatable in response to fluid pressure communicating therewith through said orifice.

2. Apparatus as described in claim 1 for sampling the fluid content of geological formations and the like, in which said temporary closure is formed in a large cup-shaped head member secured at said one end of said projectile and prevents communication between the interior and exterior thereof, the surface area of said temporary closure being very small in relation to the over-all surface area of said head member, whereby said head member will not penetrate any substantial distance into the wall 30 of a bore hole when projected thereagainst.

3. Apparatus for sampling the fluid content of geologic formations and the like, comprising a hollow tubular projectile adapted to be projected into a formation and having an orifice in the forward end wall thereof communicating with a fluid storage chamber therein, a member secured to the forward end wall of said projectile and having a portion extending axially of said orifice and terminating in a piston in said storage chamber, valve means having a bore with a bottom wall at one end in which said piston is adapted to be snugly received for relative sliding movement between said piston and valve means, the bottom of said piston normally lying adjacent one side of the bottom wall of said bore with said valve means closing said orifice and the other side of said bottom wall being exposed to the pressure in said storage chamber, stop means in said chamber limiting rearward travel of said valve means, and a cup-shaped head member tightly fitted on said forward end of the projectile and cooperating with said end wall to form a fluid receiving chamber, said head member including means forming a temporary closure preventing communication between the interior and exterior of said fluid receiving chamber.

4. Apparatus for sampling the fluid content of geologic formations and the like, comprising a hollow tubular projectile having a wall at the forward end thereof provided with an orifice therein, a rear closure member for said projectile cooperating therewith to form a fluid storage chamber therein, a perforated disc-like member secured to said wall at the forward end of said projectile and carrying a member extending axially of said orifice and terminating in a piston in said storage chamber, valve means having a bore with a bottom wall at one end in which said piston is adapted to be snugly received for relative sliding movement therebetween, the bottom of said piston normally lying adjacent one side of the bottom wall of said bore with said valve means closing said orifice and the other side of said bottom wall being exposed to the pressure in said storage chamber, stop means in said storage chamber limiting rearward travel of said valve means, a cup-shaped head member tightly fitted over the forward end of said projectile and cooperating therewith to form a fluid receiving chamber communicating with said orifice, means defining an opening 70 portion in the front end of said head member, and frangi-

ble closure means for said opening portion adapted to be rendered ineffective upon impact with a formation, said head member being made of a relatively malleable metal and having a forward surface shaped in the form of a frustum of a cone of large apex angle.

5. Apparatus as defined in claim 4 in which said head member is made of aluminum.

6. Apparatus for sampling the fluid content of geologic formations and the like, comprising a hollow tubular projectile having a wall at the forward end thereof provided with an orifice therein, a rear closure member for said projectile cooperating therewith to form a fluid storage chamber therein, a member secured to the forward end wall of said projectile and having an end portion extending axially of said orifice in the direction of said storage chamber, valve means inside said storage chamber normally seated on said forward end wall and closing said orifice, and piston and cylinder means connecting said valve means and said member end portion so as to permit relative motion therebetween to enable said valve means to be opened and closed, said piston and cylinder means comprising a piston, means forming a bore having a bottom wall at one end and in which said piston is snugly received for fluid-tight relative sliding movement therebetween in accordance with valve opening 25

and valve closing movements of said valve means, the bottom of said piston cooperating with said bore to form a closed chamber adapted to decrease and increase, respectively, in volume in accordance with closing and opening movements, respectively, of said valve means.

7. Apparatus as defined in claim 6 together with filter means preventing solid particles from entering said orifice.

8. Apparatus as described in claim 6 for sampling the fluid content of geological formations and the like, together with a cup-shaped head member tightly fitted on the forward end of the projectile forming with said forward end wall a fluid receiving chamber, said head member including means forming a temporary frangible closure preventing communication between the interior and exterior of said fluid receiving chamber.
